UNITED STATES PATENT OFFICE.

OTTO J. MOEHLER, OF NEWARK, NEW JERSEY, ASSIGNOR TO COOPER HEWITT ELECTRIC COMPANY, OF HOBOKEN, NEW JERSEY, A CORPORATION OF NEW JERSEY.

SWITCH MOUNTING.

Application filed June 21, 1927. Serial No. 200,335.

The present invention relates to electric switches of the mercury flow type and particularly to mounting means for such switches and to units comprising switches 5 and mounting means therefor.

Various objects and advantages of the invention will be obvious from the following particular description of one form of mounting and switch unit embodying the invention 10 or from an inspection of the accompanying drawing; and the invention also consists in certain new and useful features of construction and combinations of parts hereinafter set forth and claimed.

15 In the accompanying drawing there is shown for purposes of illustration one form of switch and mounting embodying the invention, in which

20 Fig. 1 is a front elevation view of a switch mounting embodying the invention and a switch carried thereby,

Figs. 2 and 3 are respectively an end view and a plan view of the mounting member of Fig. 1,

25 Fig. 4 is a sectional view taken along the line 4—4 of Fig. 5,

Fig. 5 is a sectional view taken along the line 5—5 of Fig. 3,

30 Fig. 6 is a bottom plan view of the mounting of Fig. 1 and

Figs. 7 and 8 are respectively face and side views in elevation of a strap member used for mounting the switch to the mounting member.

35 Fig. 9 is a side elevation view of a strap member similar to that of Figs. 7 and 8 but having a spring clip for attaching conductor leads.

In the drawing the rigid mounting block 1 is preferably of insulating material such as bakelite, hard rubber, or other insulating material and is of elongated shape to suit the length of the mercury tube switch 3 which latter has mounted on one of each end thereof 40 a metal cap 4—4 which connects with a respective one of the electrodes 6, 6 of the switch. Said member 1 on its bottom side is provided at each end with a pair of projections 8, 8 having inclined inner surfaces 45 adapted to receive a respective cap 4 and to support it against lateral movement. This relation is indicated in Fig. 4. For securing the switch 3 to the mounting member 1 a strap 10 is provided one at each end, it being soldered to a respective cap 4 and bolted to

the mounting member 1. Bolts 12, 12 and the nuts 14, 14 secure the straps 10, 10 to said member 1, but the straps themselves and the member 1 are in the preferred embodiment of the invention formed to hold the switch 3 and straps 10, 10 in place on the member 1 without the aid of said bolts and nuts 12 and 14. These bolts and nuts 12 and 14 are used to positively secure the straps 10, 10 to the member 1 and also to secure electrical leads 60 to said straps 10, 10 for connection therethrough with said terminals 6, 6 of the switch. Each of said straps 10, 10 comprises a main longitudinal portion having an opening 16 therethrough near one end on each side of 70 which is formed on the strap 10 a wing or vane 18 for guiding and holding in place the end of an electric conductor fastened under the head of a respective bolt 12 or washer 20 therat. At its upper end there extends a 75 portion 22 from the main part of strap 10 at right angles therewith and in a direction away from said vanes 18, 18, and said member 1 at each end on its upper surface has formed 80 therein a downward recess 24 into which a respective member 22 fits so that it is even and flush with the upper surface of member 1. At a short distance from each end of member 1 there extends downwardly from said depression 24 a deeper depression 26 85 adapted to receive a nut 14. This depression 26 is of such width that its sides will serve to prevent rotation of the nut therein when the screw is being turned therein. In the form shown the width of the member 22 is the same 90 as the width of the nut 14 so that the width of said depression 26 is the same as that of depression 24. In the end wall of member 1 and connecting with said depression 24 is the vertical slot 28 adapted to receive the stem of 95 the bolt 12 with nut 14 thereon, and at the back of said depression 26 is provided the depression 30 to receive the end of the bolt 12. To reduce the weight of said member 1 it is formed with a cavity 32 therein extending 100 upwardly of its lower surface, this cavity 32 serves to receive the seal off tip 34 of the glass envelope of switch 1 which in the assembled position extends upwardly, it also serves to receive the electrode cup 38 in certain cases as shown where the switch is mounted above the backing member 1. In such case the cup 38 is made of a size and at a position to fit into the depression. Mounting holes 36, 36 extending transversely are 110

provided in member 1 with bosses 38, 38 formed thereat between the sides of said depression 32.

In assembling the switch sleeve to mounting block 1 the strap 10 is mounted at each end of member 1 and the bolt 12 thereof tightened to hold them firmly in place. A switch envelope 3 having the ends of the caps 4 thereof tin and provided with a body 10 of solder is mounted with said caps 4 resting between respective parts of said projections 8, 8 and with the seal off 34 or cup 38 extending into the said depression 32. The straps 10 are then pressed against respective caps 4 and heated to melt the solder on the cap and to solder the strap to the cap. The strap is preferably made of brass nickel-plated or tinned. In this arrangement as will be apparent from the drawing and the 15 above description when the straps are in position on the block 1 and are soldered to the caps 4, 4 of the switch 3 the member 22 of the strap will hold the nut 14 in place even when the bolt 10 is not screwed thereinto, and the strap through the extension 22 and said depression 24 to hold the switch in position on block 1, fitting the caps 4, 4 between the 20 projections 8 co-operating in this function. It can be seen then that electric connection 25 could be made to the switch terminal 6 by attaching leads directly to said straps 10 or caps 4, 4 and that the bolts and nuts 12, 14 could be dispensed with, however, in the preferred form the bolts and nuts are used to 30 positively clamp each strap to the mounting member 1 and attach conductor leads to the straps 10 for connection therethrough to the 35 switch terminals.

In Fig. 9 is illustrated an alternative embodiment in which the strap 10 has a clip 40 of the Fahnestock type for securing electric leads thereto. This clip 40 takes the place of the bolt and nut 12, 14 of the other embodiment and the mounting and securing of the switch 3 to backing 1 is fully attained through the nesting of the switch between said projections 8, 8, the fitting of said members 22, 22 into said depressions 24, 24 and the bearing of said straps 10, 10 against the ends of backing 1.

While I have shown and described and have pointed out in the annexed claims certain novel features of the invention, it will be understood that various omissions, substitutions and changes in the forms and details of the device illustrated and in its use may be made by those skilled in the art without departing from the spirit of the invention.

I claim:

1. In a switch unit, in combination, a mercury tube switch, a rigid backing member therefor, and mounting members secured to said switch and engaging said backing member, said backing member being recessed to

receive said switch, the sides of the recess being adapted to prevent lateral movement of the switch with respect to the backing member, said mounting members having lateral projections and said backing member having recesses to receive said lateral projections, said lateral projections and recesses serving to prevent lateral movement of said mounting members with respect to said backing member.

2. In a switch unit, in combination, a mercury tube switch, a rigid backing member therefor, and mounting members secured to said switch and engaging said backing member, said backing member being recessed to receive said switch, the sides of the recess being adapted to prevent lateral movement of the switch with respect to the backing member, said mounting members having lateral projections and said backing member having recesses to receive said lateral projections, said lateral projections and recesses serving to prevent lateral movement of said mounting members with respect to said backing member and said mounting members bearing against said backing member to prevent longitudinal movement of said switch with respect to said rocking member.

3. In a switch unit, in combination, a mercury tube switch, a rigid backing member therefor, and mounting members secured to said switch and engaging said backing member, said backing member being recessed to receive said switch, the sides of the recess being adapted to prevent lateral movement of the switch with respect to the backing member, said mounting members having lateral projections and said backing member having recesses to receive said lateral projections, said lateral projections and recesses serving to prevent lateral movement of said mounting members with respect to said backing member, said mounting members being of conductive material and connected with the electrodes of said switch, and means on said mounting members for making electrical connection therethrough to the electrodes of the switch.

4. In a switch unit, in combination, a mercury tube switch, a rigid backing member therefor, and mounting members secured to said switch and engaging said backing member, said backing member being recessed to receive said switch, the sides of the recess being adapted to prevent lateral movement of the switch with respect to the backing member, said mounting members having lateral projections and said backing member having recesses to receive said lateral projections, said lateral projections and recesses serving to prevent lateral movement of said mounting members with respect to said backing member and said mounting members bearing against said backing member to prevent longitudinal movement of said switch with respect to said

backing member, said mounting members being of conductive material and connected with the electrodes of said switch, and means on said mounting members for making electrical connection therethrough to the electrodes of the switch.

5. A mercury tube switch having electrodes sealed therewith, a rigid backing member of insulating material co-extensive with said switch and recessed at one face to receive the switch, said backing member having a recess extending inwardly from each end thereof, rigid mounting members mounted to said electrodes one at each end of the switch and extending over the ends of said backing member and into said inwardly extending recesses, the seating of the switch in the first said recessed face serves to prevent lateral movement of the switch with respect to the backing member, 10 said inwardly extending members serving to prevent lateral movement of said mounting members with respect to said backing member, and said mounting members serving to prevent longitudinal movement of the switch with respect to the backing member.

20 25 with respect to the backing member.

6. A mercury tube switch having electrodes sealed therewith, a rigid backing member of insulating material co-extensive with said switch and recessed at one face to receive the switch, said backing member having a recess 30 extending inwardly from each end thereof at a face opposite to the first said recessed face, rigid mounting members mounted to said electrodes one at each end of the switch and extending over the ends of said backing member and into said inwardly extending recess, the seating of the switch in the first said recessed base serving to prevent lateral movement of the switch with respect to the backing member, said inwardly extending members 35 40 45 serving to prevent lateral movement of said mounting members with respect to said backing member, and said mounting members serving to prevent longitudinal movement of the switch with respect to the backing member.

Signed at Hoboken, in the county of Hudson and State of New Jersey, this 15th day of April, A. D. 1927.

OTTO J. MOEHLER.
